Primary Examiner — T Chase Nelson

(57) **CLAIM**

The ornamental design for a spray booth as shown and described.

DESCRIPTION

Spray Booth

4.1 : Front Perspective View

4.2 : Rear Perspective View

4.3 : Front Elevation View

4.4 : Rear Elevation View

4.5 : Left Side Elevation View

The broken lines show portions of the spray booth that form no part of the claimed design.

1 Claim, 5 Drawing Sheets
